3 Claims. (Cl. 164—17)

The present invention relates to a method of producing scroll-edged metal blanks.

It is a present custom where automatic machinery is employed in cutting a number of articles from a sheet of tinplate, or the like, to first sever the sheet into blanks by a shearing machine and subsequently to feed the blanks so obtained through a press for the cutting of the desired articles. When the articles are of circular configuration such, for example, as can ends, a more economical cutting is obtained in a cutting layout embodying adjacent rows of articles arranged in staggered relationship.

The present invention contemplates the method of shearing a blank containing adjacent staggered rows of can end providing spaces; the improved blank representing the maximum economy of cutting while providing a blank which can be efficiently handled in the automatic production of the desired articles.

One form of shearing machine suitable for practicing the present method and for producing an improved blank according to the present invention is embodied in the apparatus disclosed in my pending application, Serial Number 339,553 on Shearing machine, filed in the United States Patent Office on February 13th, 1929. The present method is disclosed in said application and the present application is a division thereof.

The principal object of the present invention is the provision of a method of dividing a sheet of metal into scroll-edged metal blanks by action of a single line cutting mechanism, the blank so produced containing spaces for can ends arranged in a double row, one row containing one more can end space than the other row.

Another important object of the invention is the provision of a method of cutting and feeding a sheet of metal to a scroll-edged cutting die whereby a blank is produced containing can end providing spaces arranged in a plurality of rows, the spaces in one row being in staggered relation to those in an adjacent row, the scroll edges of the blank closely fitting such can end spaces.

An important object of the invention is the making of a blank having a scroll formation along two opposed edges and containing two rows of can end providing spaces arranged in staggered relation the scroll-edged outline closely fitting the can end spaces and providing a blank of uniform width and contour from which can ends may be cut with a minimum waste of material.

Numerous other objects and advantages of the invention will be apparent as it is better understood from the following description, which, taken

in connection with the accompanying drawings, discloses a preferred embodiment thereof.

Referring to the drawings:

Figure 1 is a longitudinal section taken through a typical apparatus for performing the present invention.

Fig. 2 is a diagrammatic partial plan, partial sectional view illustrating a sheet in first operating position.

Fig. 3 is a view similar to Fig. 2 illustrating a sheet in second operating position.

Fig. 4 is a view similar to Fig. 2 illustrating a sheet in a subsequent operating position.

The machine, of the scroll shear type, illustrated in connection with the present application comprises a table or bed 11 formed as a part of a base 12. Base 12 is connected with a bolster plate 13 of the scroll shear, the plate 13 supporting a die plate 14 on which is positioned a lower die cut edge 15 having a scroll cutting surface 16.

Sheets 17 are moved over the upper surface of the table 11 and over the lower die member 15 in a series of intermittent forward movements. In each position of rest, the sheet 17 is engaged by a punch member 18 formed with a scroll edge 19 adapted to cooperate with the scroll edge 16 of the die 15 and produces a winding cut. Punch member 18 is carried on a punch plate 21 moving with a press slide 22 of the usual and preferred construction.

The sheet 17 is advanced over the table 11 by a feeding device comprising a feed bar 23 having reciprocating movement within a slot 24 formed in the table 11. Spring pressed dogs 25 are positioned in slots 26 cut in the bar 23, the dogs having pivotal movement on pivot pins 27 carried by the bar 23 and being held in normal raised position by leaf springs 28.

Reciprocation of the feed bar 23 causes engagement of one of the feed dogs 25 with the rear edge of the sheet 17 and advances it in a step by step movement. Other dogs 29 are pivoted on pins 31 carried by a retaining bar 32 positioned above and held in spaced relation to the sheet 17. When the rear edge of the sheet 17 passes a dog 29, the dog drops downwardly by gravity to the position illustrated in the left-hand dog 29 in Fig. 1. This holds the sheet 17 and prevents it returning with the return movement of the feed bars 23. Each dog 29 is formed with a lateral opening 33 which surrounds a pin 34 positioned on the bar 32 and this construction permits a limited movement of the dog while preventing displacement thereof.

Plate 21, besides carrying the punch cutting member 18, carries an auxiliary punch member 35 and a notching punch member 36. Members 35 and 36 cooperate with corresponding die parts 5 carried on the bolster plate 13 to cut certain notches from the sheet 17 as it is moved through the machine.

Sheet 17 (Figs. 2, 3 and 4) is adapted to be cut into blanks and when the blanks are to be 10 used for circular articles, such as can ends, a stagger layout is used, this type of layout being more economical of the material in the sheet. Sheet 17 may be said to have a series of potential can end providing spaces and the outline of one 15 cutting layout herein illustrated shows the can blank or disc by dotted circular lines. These circles are arranged in rows, one row being adjacent the edge of the sheet and each disc being in staggered relation, this insuring the maximum 20 efficiency in sheet cutting.

When sheet 17 is brought to its first cutting position, illustrated in Fig. 2, the punch members 18, 35 and 36 make their downward stroke and cooperate with their associated die members. In this first cutting action, there are severed from the front edge of the sheet two corner pieces 41 one of which is removed from each 25 forward corner by the punch member 35. There is also removed from the sheet two rectangular pieces 42 obtained by the cutting action of the 30 punch members 36.

For the purpose of clearer illustration, the severed parts 41 and 42 are shown on the right-hand side of Fig. 29 as being separated or removed 35 from the sheet 17. This is merely a diagrammatic showing of the operation and does not truly indicate relative positions of the parts during the cutting operation.

Sheet 17 upon being advanced to its second 40 cutting position (Fig. 3) has certain parts removed, these comprising a front trim piece 43 resulting from the action of the punch member 18, two corner pieces 44 cut by action of the member 18 from the two opposite front corners 45 of the sheet, end pieces 45 severed from the sheet by the punch members 35 and rectangular pieces 46 similar to the pieces 42 previously mentioned resulting from a cutting action of the member 36.

A front scrolled edge 47 results from this trimming action in the second operation, by reason 50 of the winding cut of the scroll surfaces 16 and 19 and embodies spaced projecting parts 48. The sheet is shaped by the cutting actions now being described, to provide a long section 49 containing 55 a row of end providing spaces 51 and there is provided a short section 52 which contains a row of can end providing spaces 51 adjacent to and in staggered relation with the spaces 51 of the long section. This short section is adjacent 60 to the long section and lays between certain side edges of the sheet formed by the removal of the pieces 45.

Following the next advance location of the sheet 17 in the scroll dies, the third cutting operation takes place (see Fig. 4) at which time the punch member 18 cuts a scroll edge 53 by severing a blank 54 from the remaining part of the sheet 17. This blank contains one long section 49 of can end providing spaces 51 and an adjacent short section containing a short row 52 of the spaces. By reason of the long section and the short section construction there is one less can end providing space in the latter.

At the time the blank 54 is removed from the front of the sheet, other parts 44, 45 and 46 are

being severed from the edges of the sheet. These parts are removed from the sheet as an incident to proper shaping of the same for production of the two row blank. While in many cases the pieces 45 are available for use in the manufacture 80 of smaller container parts the pieces 41, 42, 43, 44 and 46 are usually discarded as being too small for use.

The forming of parts of the sheet and the final severing of a blank 54 therefrom continues 85 throughout the entire length of the sheet at each cutting operation, the same cutting mechanism acting in synchronism with the advance movement of the sheet 17 by the sheet feeding device.

The particular form of the blank 54 produced in carrying out the present invention is particularly adapted to subsequent feeding in automatic machinery for removing can ends or other articles 90 from the providing spaces 51. It will be evident that the cutting off of one blank 54 properly spaces the front edge of the sheet for the next blank to be severed therefrom.

The outer edges or the outline of the blanks 54 are positioned adjacent the can end providing 100 spaces a minimum distance to insure a proper subsequent cutting action in removing the can end and this provides a blank having a total area only slightly in excess of the usable area of the combined can end providing spaces. This provides a blank that is easily handled in automatic 105 machinery and at the same time presents a high degree of cutting efficiency.

It is thought that the invention and many of its attendant advantages will be understood from the foregoing description, and it will be apparent 110 that various changes may be made in the form, construction and arrangement of the parts without departing from the spirit and scope of the method or sacrificing all of its material advantages, the details hereinbefore described being 115 merely a preferred performance thereof.

I claim:

1. The method of producing scroll-edged metal blanks, which comprises cutting a sheet of metal at an interval with scroll cuts, producing blanks 120 of the same scroll formation along two opposed edges thereof, each blank when so cut comprising a long section extending longitudinally and an adjacent short section also extending longitudinally, said long section providing spaces for 125 a given number of can ends, and said short section providing spaces for a less number of can ends, the indented parts of the scroll at one edge of the blank being opposite to and in line with the projected parts of the scroll at the other edge of the blank, and during said interval feeding the sheet for a distance which will contain two rows of can ends, whereby said blanks provide material for can ends with the minimum amount of wastage in subsequent can end cutting.

2. The method of producing scroll-edged metal blanks formed of a double row of can ends providing spaces, which comprises cutting a sheet of metal at intervals with winding cuts producing a series of said blanks of equal size and shape, each blank having a scroll formation along two opposed edges and containing an even number of rows of can ends providing spaces, said spaces in one row being one less in number and being in staggered relation to the spaces in the other 140 row, whereby said spaces adjacent the scroll edges of the blank extend into the wider parts thereof to produce a minimum area of blank in excess of the combined area of said can end providing 145 spaces, and feeding the sheet between cuts a dis-

tance equal to an even number of rows of can ends when the latter are arranged as described.

which the disks of one row will alternate with the disks of the other row, and then severing the sheet by a similar scroll-cut.

3. The method of producing scroll-edged sheet metal blanks, which comprises severing a sheet of metal by a scroll-cut, then feeding the sheet a distance to furnish two rows of disk-spaces in
